UNITED STATES PATENT OFFICE.

JOHN DUFFY, OF CHICAGO, ILLINOIS.

FUEL-MIXER.

1,347,997.

Specification of Letters Patent. Patented July 27, 1920.

Application filed December 3, 1917. Serial No. 205,084.

To all whom it may concern:

Be it known that I, JOHN DUFFY, a citizen of the United States, and a resident of the city of Chicago, county of Cook, and State 5 of Illinois, have invented certain new and useful Improvements in Fuel-Mixers, of which the following is a specification.

My invention relates to improvements in fuel mixers for use in conjunction with internal combustion engines, and adapted to supply a mixture of air and steam to the explosive charge, the object of the invention being to provide a simple and efficient device of this character which may be readily applied to any of the usual forms of such engines, and which is capable of uniform 15 operation.

The invention consists in the combinations and arrangement of parts hereinafter described and claimed.

The invention will be best understood by reference to the accompanying drawings forming a part of this specification, and in which,

25 Figure 1 is an end view of a fuel mixer embodying the invention,

Fig. 2, a view of the opposite end thereof,

Fig. 3, a top plan view corresponding with Fig. 2,

30 Fig. 4, a vertical section of a valve corresponding with Fig. 1, and

Fig. 5, a section taken on line 5—5 of Fig. 2.

The preferred form of construction as 35 illustrated in the drawings comprises a cylindrical casing 6 having a threaded stud 7 at one end thereof, and by means of which the device may be readily mounted on the exhaust manifold of an ordinary internal combustion or explosive engine. The casing 6 is provided at one side with a horizontally 40 extending threaded nipple 8, adapted to receive the end of a pipe 9, which in turn is connected with the intake pipe of the engine. At its opposite side casing 6 is provided with another threaded nipple 10 leading horizontally thereinto and connected 45 with a pipe 11, which leads to the water jacket of the engine for supplying water to the device. The passage of nipple 10 leads to a port 12 leading into the interior of casing 6 and controlled by a needle valve 13,

as shown. A plurality of air inlet openings or ports 14 are provided in the closed end of casing 6, a hollow rotary valve 15, operating 55 in casing 6, being inserted therein through the open end thereof. Valve 15 is rotatably mounted on a central stem or stud 16 projecting from the closed end of casing 6, through the open end thereof, and said 60 valve is held to its seat by means of a compression spring 17, as shown. Valve 15 is provided with an outlet port 18 arranged to register with the nipple 8 to permit the passage of air and steam to the engine intake 65 through pipe 9, and a peripheral groove 19 is provided in valve 15 to register with port 12, and leading to a port 20 to admit water from pipe 11 to the interior of valve 15. The inner end of valve 15 is closed by a 70 plug 21 having ports 22 therein, adapted to register with the ports 14, as shown, the outer end of valve 15 being closed by a plate 23 formed integrally therewith. Plate 23 is provided with two substantially diametrically disposed operating arms 24 formed integrally therewith, and two substantially diametrically disposed supporting arms 25 are formed integrally with casing 6 and provided with threaded sockets 26 at 80 their outer ends. The sockets 26 are arranged to receive the outer casing or flexible pipe 27 of a Bowden wire, the interior wire 28 thereof being arranged to be connected with the corresponding arm 24 which is perforated for the purpose.

By this arrangement it will be observed that the Bowden wire may be readily connected with either of the arms 24, and that operation of said Bowden wire by applying 90 tension thereto, will serve to open the valve 15 to permit passage of air and steam to the engine intake, and that compression applied to the Bowden wire will close said valve. Thus the device may be applied to any ordinary internal combustion or explosive engine and the Bowden wire operating connection led in either direction therefrom, without altering the method of operating the Bowden wire to operate the valve. Water 100 admitted to the device through nipple 10 is converted into steam during its passage through the groove 19 from the heat of the exhaust, and is thoroughly mixed with a

suitable quantity of air before being supplied to the explosive mixture. The plurality of air inlet ports 14—22 serve to supply ample air to the device without noise, and 5 the valve is so designed and constructed that the more the port 12 is opened to admit more water, the more ports 14 are opened to admit more air and thus regulate this supply of air in proportion to the amount of 10 water admitted. The specific form and arrangement of parts is a simple and efficient one for the purpose.

While I have illustrated and described the preferred form of construction for carrying my invention into effect, this is capable of variation and modification without departing from the spirit of the invention. I, therefore, do not wish to be limited to the precise details of construction set forth, 20 but desire to avail myself of such variations and modifications as come within the scope of the appended claims.

Having described my invention what I claim as new and desire to secure by Letters Patent is:

1. A device of the class described comprising a casing; a rotary valve member in said casing; means for supplying water to said casing and conducting the same away, 30 said means being controlled by said valve; substantially diametrically projecting operating arms on said valve; substantially diametrically disposed sockets on said casing coöperating with said arms; and an operating connection for said arms arranged to be mounted in either of said sockets and operatively connected with either of said operating arms, substantially as described.

2. A device of the class described comprising a hollow cylindrical casing open at one end and having one or more air ports eccentrically positioned in its other end; a hollow rotary valve mounted in said casing and closed on all sides, the inner portion of 45 said valve being provided with one or more eccentrically positioned ports adapted to be brought into registration with the air ports in said casing; and means for operating said valve, substantially as described.

50 3. A device of the class described comprising a casing; means leading horizontally from one side of said casing for connecting said casing with the intake of an engine; means leading horizontally into the 55 opposite side of said casing for admitting water thereto; ports in the end of said casing admitting air thereto; a rotary valve controlling the passage from said water and air admission means to said connecting 60 means; substantially diametrically disposed operating arms on said valve; substantially diametrically disposed sockets on said casing coöperating with said arms; and an operating connection for said arms arranged.

to be mounted in either of said sockets and 65 operatively connected with the corresponding arm, substantially as described.

4. A device of the class described comprising a hollow cylindrical casing open at one end and having a plurality of air ports 70 in its other end; a central stem projecting from the closed end of said casing through the open end thereof; a nipple leading horizontally from one side of said casing for connecting said casing with the intake of an 75 engine; a nipple leading horizontally into the opposite side of said casing for supplying water thereto; a rotary hollow valve mounted on said stem, having ports in its side walls controlling the water inlet and 80 the connection with the intake of the engine, and ports in its end wall controlling the air inlet ports; substantially diametrically projecting operating arms on said valve; substantially diametrically disposed 85 sockets on said casing coöperating with said arms; and an operating connection for said arms arranged to be mounted in either of said sockets and operatively connected with the corresponding arm, substantially as described.

5. A device of the class described, comprising a casing open at one end and having one or more air ports in its other end; a hollow rotary valve mounted in said casing and closed on all sides, the inner portion of said valve being provided with one or more ports adapted to be brought into registration with the air ports in said casing, and the outer portion of said valve projecting beyond said casing; substantially diametrically projecting operating arms secured to the outer end of said valve; substantially diametrically projecting arms secured to said casing adjacent the open end 95 thereof, each of said arms having a longitudinally extending socket adjacent the free end thereof; and an operating connection for said first mentioned arms arranged to be mounted in either of said sockets and 100 operatively connected with the corresponding arm, substantially as described.

6. A device of the class described, comprising a casing open at one end and having one or more air ports in its other end; a hollow rotary valve mounted in said casing and closed on all sides, the inner portion of said valve being provided with one or more ports adapted to be brought into registration with the air ports in said casing, and the outer portion of said valve projecting beyond said casing; operating arms integral with the outer end of said valve and projecting substantially diametrically; co-operating arms integral with said casing 115 adjacent the open end thereof and projecting substantially diametrically therefrom, each of said arms having a longitudinally 120

extending socket adjacent the free end thereof; and an operating connection for said arms arranged to be mounted in either of said sockets and operatively connected with the corresponding arm, substantially as described.

In testimony whereof I have signed my

name to this specification in the presence of two subscribing witnesses.

JOHN DUFFY.
